UNITED STATES PATENT OFFICE.

GEORGE A. LE FEVRE, OF RICHMOND HILL, NEW YORK, AND WARREN B. HUTCHINSON, OF NEWARK, NEW JERSEY, ASSIGNEES, BY DIRECT AND MESNE ASSIGNMENTS, TO PAXFLAT BARREL AND CRATE CORPORATION, A CORPORATION OF NEW YORK.

CONTAINER.

1,320,397.

Specification of Letters Patent.

Patented Nov. 4, 1919.

Application filed November 4, 1918. Serial No. 260,983.

To all whom it may concern:

Be it known that we, GEORGE A. LE FEVRE, a citizen of the United States, and a resident of Richmond Hill, Queens county, New York, and WARREN B. HUTCHINSON, a citizen of the United States, and a resident of Newark, county of Essex, and State of New Jersey, have invented a new and useful Improvement in Containers, of which the following is a full, clear, and exact description.

Our invention relates to improvements in ventilated containers, that is containers in which the staves or slats are spaced apart so as to leave air spaces between them. The objects of our invention are to make a simple and convenient form of container of this character which can be very cheaply made, very easily set up, and in which the hoops are constructed to space the staves or slats and hold them with sufficient rigidity and yet be sufficiently flexible to permit the container to be easily set up when desired. A special object of the invention is to form the container with clips struck up from the hoops, in which a pair of clips shall embrace each stave and be doubled over and preferably embedded in the stave so that the stave and hoop are permanently secured and in such a way that the holding clips are not likely to break or work loose. Our invention also lends itself to the formation of crates or containers either in cylindrical, rectangular, or other forms, the form of the crate depending on the shape of the head. Our invention is also intended to produce a simple and cheap form of hoop in which light material can be made sufficiently strong. All to the end of producing a cheap, convenient, and easily knocked-down or set up container.

Reference is to be had to the accompanying drawings forming a part of this specification, in which similar reference characters indicate corresponding parts in all the views.

Figure 1 is a side elevation of a container in barrel form embodying our invention.

Fig. 2 is a plan of the head preferably used.

Fig. 3 is a detail section showing the connection between the head and staves.

Fig. 4 is a plan view of another form of head.

Fig. 5 is a detail section showing the con-

nnection between the head in Fig. 4 and the staves.

Fig. 6 is a broken detail plan showing the hoop and staves in relative position.

Fig. 7 is a cross section through the staves showing the manner in which the hoop is fastened to the staves.

Fig. 8 is a cross section through the hoop before the holding clips have been clenched to the staves.

Fig. 9 is a detail showing the ends of the hoops spaced prior to fastening them together.

Fig. 10 shows the hoop ends fastened.

Fig. 11 shows the container in rectangular form, and

Fig. 12 is a longitudinal section of a crate showing our improvements.

We use straight staves 10 which are provided preferably near the ends with a croze 11 adapted to receive the edges of the head 12. The head is preferably a thin sheet metal head stiffened by surface corrugations 13 and preferably provided with seat portions at the edge for the several staves, and the flange 14 which fits the croze of the staves is broken at intervals as shown at 15 so that these projections fit between the staves and form lateral support, and also form the seats between them for the staves.

If desired a head 16 or other form of wooden head can be substituted for that shown. The hoops 17 are made of thin sheet metal, and are preferably corrugated longitudinally near the side edges as shown at 18 in Fig. 8 to give them additional stiffness. At intervals clips 19 are struck up from the middle portions of the hoops, and these have preferably though not necessarily, pointed ends 20. The staves 10 fit between the pairs of clips as shown clearly in Figs. 6 and 7, and the clips are clenched over upon the staves and the points 20 preferably embedded in the wood, as shown clearly in the drawings. This arrangement includes a hoop which is very easy to make by machinery, and the clips can be conveniently clenched by machinery, and furthermore by

having the staves grasped on opposite sides by the hoops in the manner shown, they are prevented from wobbling and are very securely held in place. It will be seen that with a sufficient number of staves to form

the container, the staves and hoops can be laid out flat, and when the container is to be made the staves and hoops are bent to the desired shape and the heads fitted in place.

5 The ends of the hoops can be fastened in any convenient manner. We have shown a very simple form of fastener in which the overlapping end portions of the hoops 17
10 are notched on the edges as shown at 21, and they can then be secured by a tie wire 22 or the like.

If the container is to be in rectangular shape, a head 16^a of rectangular shape is inserted in the croze of the staves, and the head as in the cylindrical form, can be either of wood or metal, but we prefer to have it of metal as shown in Fig. 2. This is an advantage because the flange 14 of the 20 head fits the croze nicely, and the head is not likely to be displaced when the container is secured at one end only, or while it is being filled. Furthermore this form of construction is desirable because the projections or bosses 15 serve to brace the staves at the ends. This form of head also lends 25 itself to the easy setting up of a knock-down structure of this kind, as the staves fit so nicely between the several bosses, that the connected staves in belt form can be rolled up around the heads and will drop nicely into place on their respective seats.

This makes it also very easy to form a 30 crate with a middle partition as in Fig. 12, in which case the staves are provided with a middle croze, and one of the heads or partitions is inserted in the croze with the 35 projections 15 between the staves as above noted.

40 The structure which we have described including the flat hoops with the integral clips struck up thereon adapted to be doubled over opposite edges of the staves,

is especially adapted to machine work, that is to say a structure of this kind can be 45 made very readily on a machine because the flat hoops can be fed through the machine easily, the clips struck up thereon, the clips doubled over upon the staves, and the structure generally finished better than ordinary 50 knock-down structures. This will be apparent upon reference to our application for 55 crate or barrel machines, Serial No. 260,982, filed November 4, 1918.

55

We claim:

1. A knock-down barrel or crate comprising a series of staves spaced apart, flat hoops connecting the staves on their outer sides, said hoops having integral clips which embrace each stave from opposite edges and are folded over upon it, said hoops having also longitudinal corrugations, and suitable heads for the crate or barrel. 60

2. In a knock-down crate or barrel, the body portion comprising a series of staves spaced apart, flat flexible hoops connecting the staves on their outer sides, clips fast upon the hoops and arranged in pairs so that each pair of clips shall embrace the stave from opposite edges, and means for 65 fastening the hoop ends together. 70

3. A knock-down crate or barrel comprising a series of staves spaced apart and connecting by flat flexible hoops thereby forming a belt-like structure, the staves each 75 having a croze therein, and head or partition members of sheet metal each having an upturned flange to fit in the croze of the stave, and outwardly extending projections to fit between the staves.

GEORGE A. LE FEVRE.
WARREN B. HUTCHINSON.
